Patented Nov. 3, 1885.

UNITED STATES PATENT OFFICE.

JOHN ROGERS, OF NEW CANAAN, CONNECTICUT.

DESIGN FOR A GROUP OF STATUARY.

SPECIFICATION forming part of Design No. 16,369, dated November 3, 1885.

Application filed October 8, 1885. Serial No. 179,370. Term of patent 14 years.

To all whom it may concern:

Be it known that I, JOHN ROGERS, a citizen of the United States, residing at New Canaan, in the county of Fairfield and State of Connecticut, have invented and produced a new and original Design for a Group of Statuary, of which the following is a specification, reference being had to the accompanying drawings, forming part thereof.

10 The group represents characters in Shakespeare's play of King Lear. The king has been mad, but he has been brought in by the doctor and his friend Kent, who now acts as his servant, and placed on a couch. His 15 daughter Cordelia, whom he has not seen since he discarded her, is seated on the couch at his feet, having her hands clasped over his knee and looking anxiously into his face. He regards her with equal earnestness, and tries to 20 recognize her as he leans forward toward her, and, with his left hand, raises the hair from her brow. He has on a long loose robe, which hangs over the side of the couch to the floor.

On the farther side of the couch stand Kent and the doctor. Kent is leaning over the king 25 and assisting him to rise. The doctor is next to Kent. He is dressed in a long robe. His left hand clasps his box of medicines and instruments, and with his right hand he is twirling the end of his beard while he watches 30 the king. On the base of the group is the quotation, "You are a spirit, I know. When did you die?"

What I claim as my invention, and wish to secure by Letters Patent, is— 35

The design for a group of statuary, representing King Lear and Cordelia seated on a couch facing each other, while two figures, representing Kent and the doctor, are standing behind the couch, all of which is herein shown 40 and described.

JOHN ROGERS.
